UNITED STATES PATENT OFFICE.

JOHN O. FASANO, OF IRVINGTON, NEW JERSEY.

TAPE GUIDE.

Application filed February 3, 1928. Serial No. 251,482.

This invention relates to a tape guide for use in sewing machines and is employed for the purpose of sewing tape in garments such as men's coats and is adapted to be attached 5 to an ordinary sewing machine now used for the purpose. It is necessary in various cuts of garments and also in affixing tape in various fabrics to vary the tension of the tape as it is fed to the needle so that it can be 10 stretched tightly or allowed to lie loosely when it is sewed to the garment. This tension is now done by hand which is rather difficult and is slow because the cloth must be fed also, being directed by hand, and the 15 tape is positioned and tensioned with the other hand.

The present invention relates to a guide which makes it necessary to guide the cloth only as the tape is directed and tensioned by 20 this device.

The invention is illustrated in the accompanying drawing in which Figure 1 is a side view of the device showing a roll from which tape is fed to the machine and showing the presser foot and support and the needle bar and its needle, the presser foot and the needle being parts of any well known form of sewing machine. Figure 2 is a section on line 2—2 in Figure 1. Figure 3 is a section on line 3—3 in Figure 1. Figure 4 is a 30 perspective of the guide.

The table of the sewing machine is illustrated at 10, the presser support is shown at 11 to which is secured the presser foot 12, this being the usual form of device with the recess 13 through which the needle 14 reciprocates, the needle being driven by the needle bar 15.

The guide is interposed between the roll or 40 source of supply of tape 16 and the needle 14 and the presser foot 12. The usual form is made of a strip of metal 17 formed into opposed plates 18 and 19 which have a spring tendency to spread from the connection 20 at one edge where they are secured together, the post 21 to the bottom plate 19 and projecting through the hole 22 in the plate 18, and the nut 23 is used to regulate the tension which in turn is controlled by the space

between the plates 18 and 19 through which 50 the tape 24 travels.

In the act of securing the tape is held close down on the cloth 25 of the garment to which it is to be affixed and is to be raised when the cloth is to be released and to make this coincide with the raising of the presser foot I usually secure the guide to the presser foot arm or support 11. Adjustment in a vertical direction is possible but I place a slot 26 in the upright plate 27 of the guard and a screw 60 55 28, which is used for securing the presser foot to the arm 12, is utilized to secure the guide in its proper vertical position. Side tilting or vibration of the guide is prevented by the flanges 29 which are secured to the upright 65 plate 27 and embrace the element to which the guide is secured. In this case the upper end 30 of the presser foot is engaged by the flanges and as the part 30 in turn is held against rotation on the arm 11 all these 70 elements are held in proper position.

It will be noted that the side 20 of the guide projects considerably beyond the part 17 and is recessed as at 31 which recess is disposed so that the presser foot can descend at its place 75 and engage the cloth of the garment. This guide conducts the tape close up to the point where it is sewed and it lies practically flat on the cloth or just above the cloth as it emerges from between the plates into the 80 space 31 where it is sewed.

In case the tape is to be taut as when it is sewed the nut 23 is turned down to cause a tighter clamping of the tape and this causes it to be held tightly so that it is stretched to 85 a slight extent when it is sewed.

I claim:

A tape guide for sewing machines comprising two plates of metal secured at one edge and having means at the other edge for adjusting the distance between the plates, the plates having an open space to expose one edge of a tape emerging therefrom to stitching, and means for securing the guide in place on a sewing machine so that said open space 90 95 is below the presser foot of the machine.

In testimony whereof I affix my signature.
JOHN O. FASANO.
